UNITED STATES PATENT OFFICE.

JAMES M. WATT, OF LATROBE, PENNSYLVANIA.

SHADE-ROLLER HOLDER.

1,278,534.

Specification of Letters Patent. Patented Sept. 10, 1918.

Application filed June 19, 1918. Serial No. 240,829.

To all whom it may concern:

Be it known that I, JAMES M. WATT, a citizen of the United States, residing at Latrobe, in the county of Westmoreland and State of Pennsylvania, have invented certain new and useful Improvements in Shade-Roller Holders, of which the following is a specification.

This invention relates generally to shade roller holders, having for its primary object to generally simplify, cheapen and improve the construction, and operation of such devices as well as to increase their efficiency.

A further object of the invention is to provide a shade roller holder capable of being easily and quickly applied to the window frame without defacing or scarring the same, and which may be adjusted to various heights upon the frame.

20 A still further object of the invention is to provide a device of the character stated which is equipped with the improved means for rendering the brackets or holding devices adjustable so as to accommodate rollers varying in lengths, and which is further equipped with means for positively holding such brackets or holders against accidental movement.

Still further objects reside in providing 30 a device of the character stated which is of inexpensive construction and which may be put upon the market at low cost, which may be readily applied to the window frame without the use of special skill or tools, 35 which is firmly held in position when properly applied, which is composed of but few simple and readily assembled parts, the said parts being so constructed and arranged as to minimize the opportunity for wear, 40 breakage or derangement, and which will prove thoroughly practical and efficient in use.

With these objects in view together with others which will appear as the description 45 proceeds, the invention resides in the novel formation, combination and arrangement of parts, all as will be described more fully hereinafter, illustrated in the drawings, and particularly pointed out in the claims.

50 In the drawings:

Figure 1 is a front elevation of a shade roller holder constructed in accordance with the invention, the view illustrating the parts

they will assume when the device is applied to a window frame, 55

Fig. 2 is a horizontal sectional view taken substantially upon line 2—2 of Fig. 1,

Fig. 3 is a vertical transverse sectional view taken upon line 3—3 of Fig. 1,

Fig. 4 is a detail perspective view of the base constituting a part of the holder, and 60

Fig. 5 is a detail perspective view of the improved locking device for the bracket to be used in connection with the holding means. 65

In carrying out the invention, a pair of the holding devices are necessary for each window, one of the said devices being arranged at each side of the window frame. Each of the holders has adjustably mounted 70 thereon, a bracket to receive the end of the shade roller and the adjustment of these brackets permits of the device being used in connection with shades varying in width. The holders at the opposing sides of the 75 frame are identical in construction, and only one, therefore, will be described.

Referring now more particularly to the drawings, 6 indicates a relatively thin metallic plate of narrow width, and this plate is 80 provided with a pair of spaced parallel longitudinally disposed openings such as the slots indicated at 7. These slots are arranged preferably near the lateral edges of the plate or base 6, and terminate at their 85 ends inwardly from the extremities of the said base. The base 6 is preferably stamped, and its end portions have apertures 8 there-in, threaded to receive suitable clamping screws, and the longitudinal edges of the 90 said base members are provided with outwardly projecting relatively narrow flange portions 9. After the plate members have been properly formed, the ends 10 are bent rearwardly at substantially right angles to 95 the body portion of the plate, and the flange portions 9 are similarly bent. The openings 8 in the end members 10 are internally threaded, and receive the clamping screws indicated at 11. The base member is applied 100 to the vertical stile of the window frame with the end portions 10 engaged over the vertical edges of the said stile, and the base is forced inwardly upon the stile until the flange or web portions 9 engage the front 105 face of the stile. The clamping screws 11

are then tightened, and the inner extremities of the same engage the sides of the stile and firmly hold the base member thereto. If preferred, the inner ends of these clamping screws may be pointed so as to bite into the woodwork. The web or flange portions 9 hold the body portion of the base spaced from the outer face of the window frame.

The base members are constructed in such manner that the ordinary or commonly used shade brackets may be employed. One of the shade brackets is indicated at 12, and is provided at one end with the usual right angularly disposed foot portion 13 having apertures therein to receive the retaining element. The base member 6 has its slots or openings 7 spaced apart a distance equal to the distance between the openings in the foot portion of the shade bracket and screws 14 are extended through the openings in the foot portion and through the slots 7 in the base member.

A clamping or locking member 15 is arranged upon the underside of the base 6. This clamping member comprises a metallic plate having a pair of spaced apertures 16 therein, the said apertures being spaced apart a distance equal to the distance between the slots 7 in the base member. The length of the clamping member 15 is preferably equal to the distance between the rearwardly projecting web or flange portions 9 so that the plate 15 fits snugly between the slots 7 in the base member. The plate at its longitudinal edges is provided with outwardly extending spaced fingers or lugs 17, these lugs being also spaced apart a distance equal to the distance between the slots 7 in the base 6. These fingers are bent forwardly at substantially right angles to the body portion of the plate 15 and when properly applied to the base members, the fingers extend forwardly through the openings or slots 7. The apertures 16 in the clamping member are threaded to receive the inner ends of the screws 14, as will be understood that when the parts are properly assembled, tightening of the screws will cause the clamping member 15 and the foot portion 13 to move toward each other and clamp upon the body portion of the base 6. When it is desired to move the brackets 12 longitudinally of the base 6, the screws 14 are loosened so as to relieve the clamping action whereupon the brackets may be freely moved. It is preferred that the width of the fingers 17 be substantially equal to the breadth of the slots or openings 7 to prevent wobbling or looseness of the brackets.

From the foregoing it is obvious that I have provided a holder for the ends of the shade rollers which is of extremely simple construction and which may be produced and placed upon the market at low cost.

The various parts of the device may be

standardized and manufactured and assembled in quantities, and the devices may be easily and quickly put together. The completed holder comprises a very small article, and will not when applied to a window detract from the appearance of the room. The holding devices may be adjusted vertically upon the stiles with great ease and after the holders are removed no unsightly marks will be left upon the woodwork. It will be noted that the distance between the base portions of the webs or flanges 9 and the outer edges thereof is greater than the distance between the outer end of screw 14 and the inner end thereof, thus obviating the opportunity for the inner extremity of the screw coming in contact with the woodwork with which the device is used.

The foregoing description and the drawings have reference to what may be considered the preferred or approved form of my invention. It is to be understood that I may make such changes in construction and arrangement and combination of parts, materials, dimensions, etc., as may prove expedient and fall within the scope of the appended claims.

Having thus fully described my invention, what I claim as new and desire to secure by Letters Patent is:

1. In a shade roller holder, a base having openings therein, a bracket having openings spaced apart a distance equal to the distance between the openings in said base, and retaining members passing through the openings in said bracket and in said base for holding said bracket upon the base.
2. In a shade roller holder, a base having openings therein, a bracket, an angularly disposed foot on said bracket, the said foot being provided with openings spaced apart a distance equal to the distance between the said openings in said base, retaining screws passing through the openings in said foot and in said base, a clamping plate, and the said screws passing through said clamping plate.
3. In a shade roller holder, a base having spaced parallel slots therein, a bracket having openings designed to align with the said slots, a clamping plate having openings spaced apart a distance equal to the distance between said slots, the said openings in said plate being threaded and screws passing through the openings in said bracket and through said slots and threaded engaged in the openings of said clamping plate.
4. In a shade roller holder, a base having a pair of spaced parallel slots, a bracket having openings designed to align with the said slots, a clamping plate having threaded openings therein spaced apart a distance equal to the distance between said slots, fingers on said plate extending into said slots, and screws passing through the openings in

said bracket and through said slots and threaded into the openings in said clamping plate.

5. In a shade roller holder, a base comprising a metallic plate, flanges projecting rearwardly from the edges of said plate and adapted to engage a support, a bracket, retaining means passing through said bracket and said plate for holding the said bracket to the latter, and the distance between the

inner and outer edges of said flanges being greater than the inward protrusion of said retaining devices.

In testimony whereof I affix my signature in presence of two witnesses. 15
